TYPEWRITING MACHINE

Russell G. Thompson, Elmira, N. Y., assignor to
Remington Rand Inc., Buffalo, N. Y., a corpora-
tion of Delaware

Application September 3, 1941, Serial No. 409,363

12 Claims. (Cl. 197—25)

This invention relates to typewriting machines, and more particularly to the type action of such machines of the type employing endwise moving type bars.

An object of the invention is to provide an improved arrangement for shifting the guiding means for each type bar to select between the printing of either of two characters as well as between either the upper or lower case printing of each character.

Another object of the invention is to provide such an arrangement for shifting the guiding means wherein the guiding means is selectively moved to definite positions at the time of printing and is retained in each of such definite positions against displacement by the reactive forces incident to the printing operation.

A further object is to provide an arrangement for shifting the guiding means of the type set forth wherein the initial forward movement of the type bar is much more rapid than the initial movement of the guiding means so that the initial force required for operation is reduced, and the type bar is moved forwardly to a position wherein it may be shifted without interference with adjacent type bars before such shifting is effected by movement of the guiding means.

Other objects, purposes and characteristic features of the present invention will appear as the description thereof progresses, during which references will be made to the accompanying drawings, wherein:

Fig. 1 is a vertical sectional view of a typewriting machine with various parts omitted and showing a type action embodying the devices of the present invention.

Fig. 2 is an enlarged, fragmentary view of the type action shown in Fig. 1 wherein certain parts are shown in their operated position for printing one of the characters on the type bar.

Fig. 3 is another enlarged, fragmentary view of the type action shown in Fig. 1 wherein certain parts are shown in a different operated position for printing another of the characters on the type bar.

The invention has been shown in the present instance as applied to a No. 10 Remington noiseless typewriting machine, and only so much of this machine has been shown in the drawings as is necessary for a full understanding of the present invention as applied thereto. Reference may be made to the patent to George G. Going No. 1,573,544 for a complete understanding of the parts of this machine which are not shown

in the present drawings and which are not necessarily modified by the present invention.

The illustrated machine includes a series of type actions mounted in different radial planes about a common printing center, and as all of these type actions are substantially the same, it is only necessary for an understanding of the present invention to specifically describe the construction and operation of one of these type actions. This type action includes a type bar 5 which is supported for endwise movement by guiding means including links 6 and 7. The two guide links 6 and 7 are pivotally connected at points 8 and 9 to the type bar 5, and these links extend downwardly from these points in substantially parallel relation.

The lower end of the front guide link 6 is pivotally connected at 10 to the end of a stationary member 11 adjustably mounted on a frame member or hanger 12 by a pin 13 and an eccentric adjusting screw 14. The lower end of the rear guide link 7 is pivotally mounted at 16 on a bell crank 17 which is in turn pivotally mounted at 18 on a shiftable arm 19. The arm 19 is pivotally mounted at 20 on the lower end of a stationary adjustable bracket 21 which is mounted by pin 22 and an eccentric adjusting screw 23 on the hanger 12.

The rearward end of type bar 5 is bifurcated with a type block mounted on the upper bifurcated portion carrying a lower case type 25 and an upper case type 26, and the lower bifurcated portion is likewise provided with a type block carrying a different lower case type 27 and a different upper case type 28. In order to selectively determine which of the types 25, 26, 27 or 28 is printed, bell crank 17 is movable to either of two positions to select between two characters and shiftable member 19 is movable to either of two positions to determine whether the selected character is printed in its lower case or upper case form. The means for moving and holding members 17 and 19 in their different positions will later be described in detail.

The hanger 12 for each type action is supported by front and rear arcuate cross members 30 and 31, the rear cross member 31 being provided with an upstanding comb portion for guiding the lower edge of type bar 5. The rear portion of each hanger 12 is provided with a slot embracing a rib on cross member 31 to afford a slight adjustment of the hanger toward and from the printing center, which adjustment is effected by a screw 32 threaded into front cross member 30 and having an annular groove receiving a

downwardly extending lug at the front end of hanger 12 in the usual manner. Each hanger 12 is retained in its adjusted position by a screw 33 threaded into the cross member 30 and having an enlarged head engaging the upper edge of the hanger.

The type bar 5 receives a forward movement in each instance by a pressure printing mechanism which may be the same as disclosed in the previously mentioned Patent No. 1,573,544. This pressure printing mechanism includes a sub lever 35 formed by parallel upstanding arms straddling a depending portion of hanger 12 and pivotally mounted at 36 at the lower end of this depending hanger portion. The upper end of sub lever 35 is pivotally connected at 37 to a weighted member or momentum accumulator 38, and a rearwardly extending arm 39 of the momentum accumulator is pivotally connected at 40 to the intermediate offset portion of a toggle link 41. The lower end of toggle link 41 is pivotally mounted at 42 on hanger 12, and the upper end of the toggle link is pivotally connected at 43 to the front end of a second toggle link 44. The second toggle link 44 is formed by two parallel strips disposed on opposite sides of the type bar 5 with their rearward ends pivotally connected at the same point 8 which joins type bar 5 with front guide link 6.

The parts of the type action are returned from actuated position to normal position shown in Fig. 1 by a contractile returning spring 46 connected between hanger 12 and a pivot pin 47 on sub lever 35, which pin also serves to pivotally mount a depending universal bar actuating member 48 of the usual construction. The parts of the type action are prevented from rebounding from normal position as they are returned from actuated position by toggle links 49 and 50 which operate in the manner fully disclosed in Patent No. 1,604,640. The rearward end of link 49 is pivotally connected at 51 to hanger 12, and the front end of link 49 is pivotally connected at 52 to the rear end of link 50 which is in turn pivotally connected at 53 to momentum accumulator 38. These links 49 and 50 are disposed in straightened relation when the parts of the type action reach normal position as shown in Fig. 1 so that the reactive force of these parts upon being arrested in this position is directed longitudinally of this straightened toggle arrangement to prevent rebound of the parts from normal position.

The type bar 5 may be operated to afford substantially noiseless pressure printing through the double toggle arrangement just described by either of two key levers 55 or 56 which are connected to individually operate sub lever 35. The key levers 55 and 56 are provided with individual keys 57 at the front ends thereof, and all of the key levers pivot about a fulcrum 58 and each lever is individually returned by a spring 59 arranged in the usual manner. The intermediate portion of key lever 55 is connected by a substantially vertically disposed link 63 to an actuating lever 64 pivotally mounted at 65 on one side of hanger 12, and the intermediate portion of the key lever 56 is likewise pivotally connected by a similar link 67 to another actuating lever 68 also pivoted at 65 to hanger 12 and disposed on the opposite side thereof from the actuating lever 64. The forwardly extending portions of actuating levers 64 and 68 are provided with curved lower edges forming treads which overlie a curved tread 70 secured on the upper

edge of a rearwardly extending arm 71 of sub lever 35.

A manual operation of either key lever 55 or 56 operates the associated lever 64 or 68 to effect a pressure printing operation of type bar 5, and this operation of the present type action does not differ materially from the ordinary Remington noiseless type action disclosed in the previously mentioned Patent No. 1,573,544. When lever 64 is operated by a depression of key lever 55, the curved lower edge of lever 64 has a rocking engagement with the curved tread member 70 to effect a changing leverage causing a rapidly accelerated movement of sub lever 35 in the usual manner. This movement of sub lever 35 operates through arm 39 to move toggle members 41 and 44 toward a straightened position as shown in Fig. 2, thereby moving type bar 5 rearwardly toward the printing position. The movement of lever 64 is limited by the engagement of the rear wall of a cut out portion therein which engages the head of pin 13, and the further movement of the sub lever 35 to its position shown in Fig. 2 is caused by the momentum of the parts which causes momentum accumulator 38 to move rearwardly sufficiently to operate toggle members 41 and 44 to substantially a straight-line position causing the final pressure printing movement of the type bar.

When lever 64 is operated from its position shown in Fig. 1 to its position shown in Fig. 2, it will be noted that the lower pivot 16 for the rear guide link 7 remains stationary. With the pivot 16 in the position shown in Figs. 1 and 2, type bar 5 moves to the printing position through a path which causes the lower bifurcated portion of the type bar to enter a type guide 75 positioned so that type 27 is pressed against a work sheet which may be carried by a platen 76. The type guide 75 and platen 76 may be of any suitable construction such as ordinarily employed in a machine of this type, but in this instance the platen 76 does not have a case shifting movement.

When lever 68 is operated by a depression of key lever 56, type bar 5 is moved toward platen 76 in substantially the same manner as when lever 64 is operated, but in this case the operation of lever 68 causes pivot 16 to move downwardly and guide type bar 5 through a path causing the upper bifurcated portion thereof to enter type guide 75 which is positioned so that type 25 is pressed against the work sheet carried by platen 76. In accordance with the present invention, the means for causing pivot 16 to move downwardly by the operation of the lever 68 includes two normally straightened toggle elements so arranged that a particularly desirable operating characteristic is produced.

Referring to Figs. 1 and 2, a rearwardly extending arm 78 on lever 68 is pivotally connected at 79 to a link 80, and the other end of link 80 is pivotally connected at 81 to an arm 82 which is pivotally mounted at 83 on the stationary hanger 12. The forward end of arm 82 is pivotally connected at 85 to a link 86, and the other end of link 86 is pivotally connected at 87 to an arm 88 also pivotally mounted at 89 on hanger 12. The lower end of arm 88 is pivotally connected at 92 to the forward end of a link 93 which is in turn pivotally connected at 94 to bell crank 17 which supports the rearward guide link 7.

An operation of lever 68 moves these levers and links from their normal position shown in Fig. 1 to their position shown in Fig. 3 wherein

movement of these parts is arrested by the engagement of the wall of a cut out portion in the upper end of arm 88 with a stationary pin 97 carried by hanger 12. The movement of bell crank 17 thus effected by the operation of lever 68 causes pivot 16 to move downwardly to a position wherein it is below pivot 18 so that the axes of pivots 16, 18 and 9 are substantially in alignment. This position of pivot 16 causes the reactive forces incidental to the printing operation of type bar 5 to be directed substantially against the dead center of pivot 18 thereby eliminating the tendency for type bar 5 to be displaced while printing.

A particular feature of the present invention is the provision of connecting means between lever 68 and bell crank 17 which includes a double toggle arrangement provided by arm 78, link 80, arm 82 and link 86. When these parts are in their normal position, link 80 assumes a straightened relation to arm 78 so that pivots 65, 79 and 81 are substantially in alignment, and likewise link 86 and arm 82 have substantially a straightened relation wherein pivots 83, 85 and 87 are all in substantial alignment. This arrangement affords a considerable mechanical advantage in the operation of bell crank 17 by lever 68 due to the operation of the toggle elements 78-80 and 82-86 from a straightened relation and due to the arrangement of these two sets of toggle elements in series whereby the leverage changing characteristics of one set of toggles is amplified by the similar leverage changing characteristics of the other set of toggles. The result is that the initial movement of lever 68 effects a very slow initial movement of bell crank 17 and the force required at lever 68 to effect this initial movement of bell crank 17 is very slight.

The above result attained by the double toggle arrangement of the present invention is very desirable in a type action of this kind because the slow initial movement of bell crank 17 allows type bar 5 to be moved rearwardly to a point wherein the adjacent type bars in their normal position do not interfere with the downward movement of the rearward end of type bar 5 caused by the movement of bell crank 17. It is also desirable in a type action to provide an arrangement resulting in a light initial operating force or "touch" of the type action. This result is attained in the present arrangement by the light initial force required to move bell crank 17 by lever 68 so that the force required to operate the type bar toward its printing position and to shift bell crank 17 by operation of lever 68 is not appreciably greater initially than the operation of the type bar by lever 64.

The double toggle arrangement associated with lever 68 also has the very important function of holding bell crank 17 against movement about its pivot 18 during operation of lever 64. When lever 68 is in normal position as shown in Fig. 1, pivots 87, 85 and 83 are in substantial alignment so that any reactive force tending to turn bell crank 17 about its pivot 18 is transmitted to lever 88 through link 93 and this force is directed substantially against the dead center of pivot 83. Likewise, pivots 81, 78 and 65 are in substantial alignment so that if any reactive force is applied to lever 82, this force is directed substantially against the dead center of pivot 65. In this manner, there is a double assurance that the reactive forces incident to the printing operation of the type bar upon operation of lever 64 cannot cause displacement of bell crank 17 about its pivot 18.

The present type action includes the usual interlocking arrangement for insuring that lever 68 is in its normal position when the type bar is actuated by lever 64. Referring to Fig. 2, this arrangement includes a crank member 100 pivotally mounted at 101 on hanger 12, and having a depending arm pivotally connected at 102 to one end of a link 103 which is connected at its other end at 104 to a depending portion on lever 64. When lever 64 is in its fully operated position as shown in Fig. 2, crank member 100 is operated about its pivot 101 to a position wherein a forwardly extending arm 105 engages the upper edge of arm 78 thereby insuring that lever 68 and parts connected thereto are in normal position when type bar 5 reaches its printing position by actuation of lever 64. Thus, the two levers 64 and 68 cannot receive an effective simultaneous operation, and it is insured that the double toggle arrangement associated with lever 68 is in straightened relation to hold pivot 16 in normal position with relation to pivot 18 when the type bar reaches its printing point by operation of lever 64.

In the present type action, pivot 16 is selectively positioned either as shown in solid lines in Fig. 2 or as shown in solid lines in Fig. 3 according to whether key lever 55 or 56 is operated and thereby selectively prints from either lower case type 27 or lower case type 25. In accordance with the present invention, the platen 76 does not receive a case shifting movement, and pivot 16 is shifted to either of two additional positions shown by dotted lines in Figs. 2 and 3 to allow printing to be effected from either of the upper case types 28 or 26 rather than the lower case types 27 or 25. Thus, means are provided in the present machine for shifting lever 19 which pivotally supports bell crank 17 between its solid line and dotted line positions shown in Figs. 2 and 3, which means also shifts type guide 75 between its solid line and dotted line positions shown in Fig. 1.

Referring to Fig. 1, type guide 75 is mounted at 110 on a shiftable frame 111. The frame 111 is guided by means not shown which may be suitably arranged to afford substantially vertical shifting movement of type guide 75 and to retain the type guide and shiftable frame against displacement in every other direction. The rearward end of an extension 112 of the arm 19 associated with each type action is received between arcuate plates 113 suitably secured in vertically spaced relation at the lower portion of shiftable frame 111. In this manner, the shifting movement of type guide 75 and frame 111 causes a pivotal movement of arm 19 of each type action about pivot 29 so that the pivots 16 of all the type actions in the machine receive a simultaneous shifting movement between the solid line and dotted line positions shown in Figs. 2 and 3.

Suitable stop means may be employed for accurately arresting the shiftable member 111 in each of its extreme shifted positions, which stop means has not been shown in the present instance. Various different arrangements may also be provided for effecting the shifting movement of frame 111, the means shown in the present instance comprising a lower extension of the shiftable member 111 which is pivotally connected at 114 to a rearward extending arm 115 rigidly secured to a rock shaft 116 mounted by suitable bearings in the frame of the machine which has not been shown. A rearwardly extending arm 117 secured to rock shaft 116 car-

ries a pin 118 received in an elongated slot 119 at the upper end of a link 120 which is pivotally connected at 121 to a T-shaped arm 122 secured to a rock shaft 123. The rock shaft 123 is suitably mounted in the frame of the machine, and the usual case shift key levers 124 are operatively connected with the rock shaft 123. The usual shift key 125 and shift lock key construction 126 are provided at the forward end of each shift key lever 124. A contractile spring 128 extends between the upper portion of the T-shaped arm 122 and a fixed pin 129 on the frame of the machine, and another contractile spring 130 extends between pin 129 and a depending arm 131 secured to rock shaft 116.

It will be clear that the spring 130 tends to move shiftable frame 111 and type guide 75 upwardly toward its dotted line position while spring 128 acts to hold the shift key levers 124 in normal position and acts through link 120 against the force of spring 130. The spring 128 is thus provided with a greater effective force so that when no downward pressure is applied to the shift key levers 124, all the case shiftable parts are retained in their downward or lower case position against the force of spring 130. However, when a downward pressure is applied to the shift key lever 124 to overcome the force of spring 128, spring 130 is effective to move the shiftable frame 111 and type guide 75 upwardly to the dotted line or upper case position. The pin 118 and slot 119 provide a one-way operative connection between the link 120 and arm 117 whereby the downward movement of shift key lever 124 is not transmitted to arm 117 so that the shiftable frame 111 and parts controlled thereby are always moved by the uniform force of spring 130 regardless of the force applied to key lever 124.

Referring to Fig. 2, it will be clear that when the case shift mechanism is operated to shift pivot 16 from its solid line position to its dotted line position, an actuation of lever 64 by key lever 55 will move type bar 5 through a path causing upper case type 28 to print rather than lower case type 27 as previously described in connection with the lower solid line position of pivot 16 shown in Fig. 2. Likewise in Fig. 3, when pivot 16 is shifted upwardly from its solid line to dotted line position, an actuation of lever 68 by key lever 56 will cause type bar 5 to move through a path which brings type 26 to the printing point rather than type 25 as previously described in connection with the lower solid line position of pivot 16 shown in Fig. 3. The upward shifting movement of pivot 16 in each instance causes a pivotal movement of type bar 5 about pivot 8 so that this case shifting movement does not in any way affect the position and operation of the toggle arrangement connecting sub lever 35 with the type bar. It will also be clear that this case shifting movement of pivot 16 causes a pivotal movement of link 93 about its pivotal connection 92 with arm 88 so that the position and functioning of the toggle 78-80 and 82-86 are not in any way affected by this case shifting movement.

A type action has thus been provided wherein the guiding means, or the guide link 7 and supporting means 17, for the endwise moving type bar are selectively moved to one of four different positions to print from one of four different types, and the type bar is retained in each of such positions against displacement by the reactive forces incident to the printing operation.

The bell crank supporting member 17 is retained in either its solid line position or its dotted line position shown in Fig. 2 against displacement during printing operation by the straightened relation of the two sets of toggle elements 78-80 and 82-86. Likewise, the reactive forces caused by printing operation do not cause displacement of member 17 from either its solid line or dotted line position shown in Fig. 3 due to the fact that pivot 16 is in each instance directly below and substantially in alignment with pivots 8 and 9 and accordingly the forces tending to displace type bar 5 are directed through link 7 against the dead center of pivot 18.

15 A further very important feature of the present invention is the provision of connecting means for shifting the pivot 16 for the type bar guide link upon operation of lever 68 which includes a double set of toggle elements. This 20 double toggle arrangement affords a variable leverage wherein the initial forward movement of the type bar is much more rapid than the initial movement of the pivot 16 so that the type bar is moved forwardly to a position wherein it may be 25 shifted without interference with adjacent type bars before such shifting is effected by the movement of pivot 16. This arrangement further provides a materially reduced initial force required in shifting the type bar guiding means which results in a light initial "touch" which more nearly 30 equals the initial "touch" in operating lever 64 which does not shift pivot 16.

In describing the present invention, attention 35 has been directed to one specific embodiment thereof, without attempting to point out the various alternate or optional features of construction, or the different organizations or combinations that may be employed. For example, the 40 double toggle arrangement for operatively connecting the lever 68 with the bell crank 17 may be used in a typewriter arrangement wherein the platen is mounted for case shifting movement and the bell crank 17 is pivotally mounted at 18 on a stationary member in the usual manner.

In other words, the particular embodiment of 45 the present invention has been selected to facilitate the disclosure thereof rather than to limit the number of forms which it may assume.

The invention claimed is:

50 1. In a typewriting machine, the combination of a type bar, guiding means for said type-bar, a case shiftable support, supporting means for said guiding means movably mounted on said case shiftable support, a relatively fixed support, and means for moving said supporting means for the guiding means on said case shiftable support including a first arm pivotally mounted on said fixed support, a second arm pivotally mounted on said fixed support, a link connecting said first and second arms and normally aligning with said first arm to form a straightened toggle, a third arm pivotally mounted on said fixed support, a second link connecting said second and third arms and normally aligning with said second arm to form another straightened toggle, and a third link connecting said third arm with said supporting means for the guiding means to afford shifting movement of the latter with said case shiftable support and relative to said third arm.

70 2. In a typewriting machine, the combination of a type bar, guiding means for said type bar, a case shiftable support, supporting means for said guiding means movably mounted on said case shiftable support, a relatively fixed support, and means for moving said supporting means for

the guiding means on said case shiftable support including a first arm pivotally mounted on said fixed support, a second arm pivotally mounted on said fixed support, a link connecting said first and second arms and normally aligning with said first arm to form a straightened toggle, and means connecting said second arm with said supporting means for the guiding means to afford shifting movement of the latter with said case shiftable support and relative to said second arm.

3. In a typewriting machine, the combination of a type bar, guiding means for said type bar, a case shiftable support, supporting means for said guiding means movably mounted on said case shiftable support, a relatively fixed support, actuating means for said type bar including two independently operable levers pivotally mounted on said fixed support, an arm pivotally mounted on said fixed support and disposed transversely of said levers, a link connecting one of said levers with said arm and normally disposed in alignment with the lever to form a straightened toggle, and means operatively connecting said arm with said supporting means for the guiding means to afford movement of the latter with said case shiftable support and relative to said arm.

4. In a typewriting machine, the combination of a type bar, a case shiftable support, a type bar supporting and guiding means movably mounted on said case shiftable support, a plurality of actuating means for said type bar, and toggle members connecting one of said actuating means with said type bar supporting and guiding means to move the latter on said case shiftable support upon operation of the type bar by said one of the actuating means, said toggle members being disposed in straightened relation in the normal position of said one of the actuating means to hold said type bar supporting and guiding means against movement on said case shiftable support during operation of the type bar by the other of said actuating means.

5. In a typewriting machine, a series of end-thrust type bars, a pair of guide links pivoted at one end to each type bar at spaced points along the length of the latter, means pivotally supporting each pair of guide links at the other end thereof, the means supporting one guide link of each pair being movable, case shifting means for simultaneously shifting all of said means movably supporting one guide link of each pair, and actuating means for each type bar including toggle members for holding said means movably supporting one guide link of each pair against movement relative to said case shifting means regardless of the shifted position thereof.

6. In a typewriting machine, the combination of a type bar, pivoted guide links for said type bar, a case shiftable support, a bell crank having one arm pivotally connected to one of said guide links, means pivotally mounting said bell crank on said support for movement from normal position thereon to a position wherein the pivots of said guide link are in substantial alignment with the pivotal mounting means for the bell crank, and means for causing said movement of said bell crank on said support including toggle members disposed in straightened relation in the normal position of the bell crank.

7. In a typewriting machine, the combination of a type bar, pivoted guide links for said type bar, a case shiftable support, a bell crank having one arm pivotally connected to one of said guide links, means pivotally mounting said bell crank on said support for movement from normal position thereon to a position wherein the pivots of said guide link are in substantial alignment with the pivotal mounting means for the bell crank, and means for causing said movement of said bell crank on said support including toggle members disposed in straightened relation in the normal position of the bell crank and link means between said toggle members and said bell crank for affording shifting movement of said bell crank with said case shiftable support without moving said toggle members.
8. In a typewriting machine, the combination of a type bar, printing keys, means for connecting each of said keys with the type bar, a case shiftable support, a type bar supporting member movably mounted on said case shiftable support, and toggle members for holding said type bar supporting member against movement relative to said case shiftable support during operation of the type bar by one of said printing keys.
9. In a typewriting machine, the combination of a type bar, printing keys, means for connecting each of said keys with the type bar, a case shiftable support, a type bar supporting member movably mounted on said case shiftable support, and toggle members controlled by one of said printing keys for holding said type bar supporting member against movement relative to said case shiftable support during operation of the type bar by the other of said printing keys.
10. In a typewriting machine, the combination of a type bar, a case shiftable support, type bar supporting means movably mounted on said case shiftable support, actuating means for said type bar, and toggle members controlled by said actuating means for normally holding said type bar supporting means against movement relative to said case shiftable support.
11. In a typewriting machine, the combination of a type bar, a case shiftable support, type bar supporting means movably mounted on said case shiftable support, actuating means for said type bar, and toggle members connected between said actuating means and said type bar supporting means and arranged to assume a substantially straightened relation when said actuating means is in normal position regardless of the position of said case shiftable support.
12. In a typewriting machine, the combination of a type bar, two printing keys for individually operating said type bar, a movable type bar supporting and guiding means, and two sets of normally straightened toggle members arranged in series between one of said printing keys and said type bar supporting and guiding means for moving the latter with increasing acceleration upon operation of said one of the printing keys and for holding the type bar supporting and guiding means against movement upon operation of the other of said printing keys.

RUSSELL G. THOMPSON.
